UNITED STATES PATENT OFFICE.

JOHN W. LONGSTRETH, OF WAYNESBURG, PENNSYLVANIA.

FIRE-EXTINGUISHER.

1,346,035.

Specification of Letters Patent.

Patented July 6, 1920.

Application filed February 9, 1920. Serial No. 357,126.

To all whom it may concern:

Be it known that I, JOHN W. LONGSTRETH, a citizen of the United States, residing at Waynesburg, in the county of Greene and State of Pennsylvania, have invented new and useful Improvements in Fire-Extinguishers, of which the following is a specification.

This invention relates to fire extinguishers and has for its object the provision of a fire extinguisher so constructed as to feed chemicals into water or other suitable liquid whereby to form a solution or gas charged liquid which will not support combustion and which will therefore be effective in putting out a fire when squirted thereonto.

An important object is the provision of a device of this character in which the construction is such that the solid chemicals will be fed uniformly into the water or other liquid, the latter flowing continually through the device.

An additional object is the provision of a device of this character which will be simple and inexpensive in manufacture, easy to use, not likely to get out of order, and a general improvement in the art.

With the above and other objects and advantages in view, the invention consists in the details of construction to be hereinafter more fully described and claimed, and illustrated in the accompanying drawings in which—

Figure 1 is a side elevation of the device, Fig. 2 is an end elevation, Fig. 3 is a longitudinal sectional view, and Fig. 4 is a vertical cross sectional view.

Referring more particularly to the drawings, the numeral 10 designates the casing which includes a lower portion 11 having a liquid inlet 12 and an outlet 13 at opposite ends thereof. Baffle plates 14 are located within the portion 11 and are arranged in inclined position, as shown.

The casing further includes a substantially cylindrical intermediate portion 15 which has a slightly tapered bore 16 and rotatably mounted within this cylindrical portion is a drum 17 also tapered and having its periphery formed with a plurality of pockets 18. At one end the drum 17 is provided with a shaft 19 journaled through the casing and at its other end is provided with a screw 20 which extends through the casing and which is surrounded by a coil spring 21, the

purpose of which is to draw the drum into close engagement with the bore.

The casing 10 further includes a laterally enlarged portion 22 located above and communicating with the cylindrical portion 15 and located within this portion are drums 23 and 24 which are star-shaped in cross section and which are adapted to rotate in opposite directions. At one end the drums 23 and 24 are provided with stubs 25 journaled through one side of the casing and at the other end are provided with stubs 26 journaled through the other side of the casing.

The casing 10 further includes a hopper 27 disposed above and communicating with the portion 22 and into which are placed the chemicals to be used.

The projecting stubs 26 carry gears 28 which intermesh and one stub is provided with a crank handle 29. One gear 28 meshes with a gear 30 suitably journaled upon the casing and this gear in turn meshes with a gear 31 secured upon the stub 19.

In the operation of the device water is passed through the lower portion 11 of the casing, passing in the inlet 12 and out through the outlet 13, and in actual practice it is of course apparent that some suitable hose or pipe be connected with the outlet 13. The chemicals are fed into the hopper 27. The operator rotates the crank handle 29 which results in movement of the drums 23 and 24 toward each other which permits the chemicals to pass from the hopper down onto the drum 17, the pockets 18 of which will of course be filled. Through the instrumentality of the gear 30 and gear 31 the drum 17 will be rotated and the pockets will be successively brought to the bottom of the casing section 15 so that the contents of the pockets will be dumped onto the uppermost baffle plate 14 and the stream of water passing over this baffle plate will carry the chemicals therefrom, onto the lower baffle plate and during this time the chemicals will be dissolved so that a chemical solution will leave through the outlet 13. It is well known that there are various chemicals which might be employed in connection with my device and it is believed that a detail statement as to what might be used is unnecessary.

While I have shown and described the preferred embodiment of my invention, it is of course to be understood that I reserve

the right to make such changes in the form, construction, and arrangement of parts as will not depart from the spirit of the invention or the scope of the subjoined claims.

5 Having thus described my invention, I claim:

1. A device of the character described comprising a casing including a lower portion provided with water inlet and outlet 10 openings, a substantially cylindrical portion located above and communicating with said lower portion, a rotary drum within said cylindrical portion having its periphery provided with pockets, said casing further 15 including a laterally enlarged portion within and communicating with said cylindrical portion, a pair of feed drums within said last named portion and rotatable in opposite directions, a hopper leading into the 20 top of said last named casing portion, and means for simultaneously rotating said feed drums and said first named drum.

2. A device of the character described comprising a casing including a lower portion provided with water inlet and outlet 25 openings, superposed baffle plates within said lower portion, a substantially cylindrical portion above and communicating with said lower portion, a rotary drum within said cylindrical portion having its periphery 30 provided with a plurality of pockets, said casing further including a laterally enlarged portion above and communicating with the cylindrical portion, and a hopper above and communicating with the laterally 35 enlarged portion, a pair of feed drums within said laterally enlarged portion and each formed star-shaped in cross section, means for rotating said feed drums in opposite directions, and means for simultaneously rotating 40 said first named drum with said feed drums.

In testimony whereof I affix my signature.

JOHN W. LONGSTRETH.
